Wis., a corporation of Wisconsin**

Application March 28, 1935, Serial No. 56,091

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily, of which the following is a specification, reference being had to the accompanying drawing, forming a part thereof.

The figure of the drawing is a face view of approximately three-fourths of a doily in outline and embodying my design. The design unit

shown in detail and enclosed by dot and dash lines constitutes one-fourth of the doily, which unit continues in regular succession to complete the substantially circular doily. One-half of the doily is defined by the vertical dot and dash lines.

I claim:

The ornamental design for a doily, substantially as shown and described.

In witness whereof, I hereunto subscribe my name this 15th day of March, 1935.

KENNETH C. HAMILTON.
